BY Hugh K. Magner,

ATTORNEY.

UNITED STATES PATENT OFFICE

MARSHALL D. GIBSON, OF WEBSTER GROVES, MISSOURI, ASSIGNOR TO JAS. H. FORBES
TEA & COFFEE COMPANY, OF ST. LOUIS, MISSOURI, A CORPORATION OF MISSOURI

DISPLAY STAND

Application filed May 4, 1929. Serial No. 360,336.

This invention relates to display stands; and the principal object of the invention is to provide a stand well adapted to support a plurality of packages in such a manner that 5 they will be effectively displayed to observers on both sides of the stand, and particularly to provide a display stand on which may be placed or stacked an indefinitely large number of articles or packages, which may be 10 gradually reduced as one after the other is sold.

Another object of the invention is to provide a stand of the character described which will be simple, rugged, and inexpensive in 15 construction.

Other objects, advantages, and desirable features of the invention will appear in the course of the following description of an illustrative embodiment thereof.

20 In the accompanying drawings forming part of this specification, in which like numbers of reference denote like parts wherever they occur,

Figure 1 is a plan view of the display stand;

Figure 2 is an end view of the same; and

Figure 3 is a front view.

The stand comprises a sheet of suitable material, preferably metal, bent on lines 1, 2, and 30 3 to define an intermediate V-shaped channel 4 to receive packages of goods 5, and flaps 6 adapted to bear display or advertising matter on their outer faces 7. The flaps 6 decline outwardly from the upper edges 1 and 3 of the walls 8 of the channel 4 and are preferably narrower than the walls 8. The bends 1, 2, and 3 stiffen the walls and flaps longitudinally. The end edges 9 of the walls 8 are beaded to strengthen and stiffen the walls 35 transversely; and the end edges 10 of the flaps 6 are beaded for the same purpose and, also, to receive the end portions 11 of wire standards 12. Each of the standards 12 comprises 40 an intermediate horizontal portion 13 that passes under the vertex 2 of the channel, and rising end portions having the oblique upper portions 11 passing through the beaded ends 10 of the similarly oblique flaps 6, and vertical lower portions 14 connecting the said up-

per portions to the respective ends of the horizontal portion 13.

It will be observed that by reason of the end portions 11 of each standard 12 being inclined in opposite directions, and the curls 55 or beads 10 of the flaps being likewise inclined, it is impossible to withdraw the said end portions from the beads without first bending both the ends 11 and the beads 10 into vertical positions. The attachment of 60 the ends 11 to the beads 10 is thereby effected in a simple and very secure manner. The packages of goods are preferably placed on the walls of the channel as shown in broken lines in Figures 2 and 3, one row of packages 65 being placed with their rear sides 15 lying against a wall 8, and another row being placed with their bottoms 16 against the front sides 17 of the first row and their rear sides 15 against the opposite wall 8 so that the front sides 17 of both rows are visible from the top of the stand and the front face 17 of at least one row of packages is always visible 70 from a respective side of the stand. Attention is directed to the fact that only three 75 parts are used in the construction of the stand and that bolts, screws, and welding and brazing operations are dispensed with. The stand is light and rigid and inexpensive. The sloping sides of the V-shaped channel, also, enables additional packages 18 to be stacked in layers on top of the first layers of packages 17, the layers alternating from one inclined side to the other, as shown in Figure 2, and so 80 forming a very stable arrangement. 85

Having thus fully described this invention, I hereby reserve the benefit of all changes in form, arrangement, order, or use of parts, as it is evident that many minor changes may be made therein without departing from the 90 spirit of this invention or the scope of the following claims.

I claim:

1. A display stand comprising a sheet of material bent to define an intermediate V-shaped channel to receive packages of goods and flaps for display matter declining outwardly from the outer edges of the channel, the said flaps being narrower than the walls 95 of the channel, in combination with a wire 100

- support at each end comprising an intermediate horizontal portion passing under the vertex of the channel and rising end portions having oblique upper portions connected to the ends of the flaps and vertical lower portions connecting the said upper portions to the respective ends of the horizontal portion.
- 5 2. A display stand comprising a sheet of material formed to define an intermediate V-shaped channel having walls to receive packages of goods, and flaps inclining in opposite directions from the outer edges of said walls, the end edges of said flaps being beaded and a standard presenting vertically disposed
- 10 15 20 25 30
- end portions having their upper ends inclined in opposite directions for insertion in the beaded end edges of said flaps to prevent displacement thereof, and an intermediate horizontal portion connecting said end portions and passing under said channel.
3. A display stand having a channel-shaped package-receiving seat and flaps inclining in opposite directions from the outer edges of said seat, the end edges of said flaps being beaded, in combination with a support, said support including rising end portions having oblique upper portions adapted to be inserted in the beaded end edges of said flaps to prevent displacement thereof.
- 30 In testimony whereof I hereunto affix my signature.

MARSHALL D. GIBSON.
